RETRACTILE MARKING IMPLEMENT

Joseph F. Kingsley, Burbank, Calif., assignor to
Nadejda V. Andrews, Los Angeles, Calif.

Application March 22, 1944, Serial No. 527,655

3 Claims. (Cl. 120—49)

1

This invention relates to a stylus-like retractile marking implement constructed, for instance, under U. S. Patents #2,291,859 and/or #2,304,229, and is an improved protrusion device in such an implement with slot apparatus whereby the implement may be adjusted and kept in a desired setting, and the efforts for changing said settings may be controlled, and the element of accidental changing said settings minimized.

In the classed types of implements different settings of their respective caps in relation to their respective barrels control supply of the marking ingredients to adapt the implement for different altitudes or temperatures affecting said supply.

When a fountain pen is filled with ink at a certain altitude or temperature and thereafter taken to a higher altitude or temperature, the change tends to force the ink from the pen under expanded air ever present in the rear of the ink container which expansion of air is affected by the difference of atmospheric pressure or temperature.

To overcome this condition certain marking implements are equipped with shut-off mechanisms dependent upon the aforesaid settings of the cap. The objects of said mechanisms are to reduce the flow, and/or shut it off either from the entire container or from a section thereof with air of original altitude or temperature.

When the implement is in the latter setting and taken to a very much higher altitude it is, evidently, of paramount importance that the setting is not changed either accidentally or through careless manipulation of one, the operating, hand, as such a change would allow the fluid to explode from the implement.

One of the objects of this invention is to provide means whereby a concentrated conscious effort of both hands would be required to effect the change of a certain setting in the implement.

Another object of this invention is to provide means allowing an average effort of one hand to open, close and lock the implement when it is in a limited setting.

Still another object of this invention is to provide means whereby a manual effort of at least one hand would be required to unlock the implement from its locked setting.

Among other objects of this invention is to make said means simple, easy to operate as instructed and inexpensive to manufacture.

To illustrate how these and other objects of this invention can be practically achieved in marking implements of varying constructions,

2

reference now is being made to the accompanying drawings.

In the drawings:

Figure 1 is a side view of a stylus-like retractile marking implement in open position and comprising structure under U. S. Patent #2,304,229 (Figure 2 thereof in reference to valves locations) and certain features of this invention.

Figure 2 shows the same implement in closed position.

Figure 3 is a side view of another implement in open position and also comprising structure under aforesaid patent (Figure 1 thereof in reference to valves locations) and features of this invention.

Figure 4 shows the latter implement in closed position.

In reference to the drawings:

Pen nibs 10 and 10A are secured to their respective barrels and the latter are stationary with their respective covers 9 and 9A. Caps 3 and 3B are slidable, turnable and held over the respective barrels and under covers 9 and 9A respectively.

Shut-off valves 2 and 2A when engaged lock air ducts in their respective barrels; shut-off valves 1 and 1A when engaged lock the ink ducts between the front and the rear chambers of implements' ink containers. Sleeves 3A and 3C are secured to caps 3 and 3B respectively and engage the valves when the caps are in dependent settings.

In Figures 1 and 2 valves 1 and 2 are on a diagonal line through the barrel, thus sleeve 3A, when moved by means of cap 3 towards nib 10 from position in Figure 1, will first engage air duct valve 2 whereby ink flow is slowed down. Then, without releasing valve 2, it will engage ink duct valve 1 whereby the rear ink chamber will become locked from the front ink chamber still exposed to outside. Finally sleeve 3A will assume position as in Figure 2 with cap 3 covering nib 10 and sleeve 3A keeping both valves (1 and 2) engaged.

To provide with features of this invention a structure where subject settings depend largely upon sliding motion of the cap like in a pen shown in Figures 1 and 2, sleeve 4 is movably mounted over cap 3 between cover 9 and protuberance 8 which is stationary with the cap 3. Sleeve 4 has a plurality of longitudinal slots 5, 5A, 6, 6A, 7 and a slot not shown, to allow protuberance 8 into the length of sleeve 4 to a full depth of an engaged slot.

When the implement is set in a position as

shown in Figure 2, sleeve 4 may be slid from shown position to the edge of cover 9. In its new position sleeve 4 may be turned either way to bring desired slot in line with protuberance 8.

It may be noted that slots 5A, 6A and unshown 7A are much shorter than slots 5, 6 or 7. When any of these relatively short slots are engaged with protuberance 8, sleeve 4, jammed between said protuberance and the edge of cover 9, will prevent cap 3 from sliding adequately far towards cover 9 to reveal nib 10 or to allow sleeve 3A to disengage valves 1 and 2.

It may be also noted that sleeve 4 walls or notches separating slots 5A from 5, 6A from 6 etc. are lower or shorter than those separating slot 5A from 6, 6A from 7 etc.

Thus it is easier to engage protuberance 8 from, for instance, slot 5 (Fig. 1) into slot 5A (Fig. 2) than from said slots into any other slots of the structure. This difference in efforts may be easily brought to bear a difference between one hand average effort from two-hands average effort. A pure mechanical skill and/or manufacturing requirements may easily determine most desired or advisable means to accommodate said efforts: For instance, differences in heights of slots separating notches, or friction between extreme edges of sleeve 4 against protuberance 8 and cover 9, a spring of dependent width and/or strength between cover 9 and sleeve 4, etc.

The different lengths of each of the relatively long slots 5, 6 and 7 naturally depend upon the extent of slide required by implement's construction from the cap 3 and protuberance 8.

In Figures 3 and 4 valves 1A and 2A are on a perpendicular line through the barrel.

Sleeve 3C engages both valves 1A and 2A simultaneously when solid walls thereof slide over said valves.

Opposite cavities, or holes, or off-sets 12 and 12A in walls of sleeve 3C may be set over valves 1A and 2A respectively (Fig. 2) whereby both of said valves will remain unengaged when sleeve 3C is slid over; a similar cavity, or hole, or an off-set 12B opposite a solid wall of sleeve 3C may be set over either of the valves allowing such valve to remain disengaged while the opposite valve will be engaged under the solid section of sleeve 3.

To provide with features of this invention a structure where subject settings depend largely upon turning motion of the cap like in the pen shown on Figures 3 and 4, the inner (rear) end of cap 3B is adapted as has been described in reference to slotted end of sleeve 4.

The protuberance (here 8A) is now stationarily secured to the pen barrel and is engageable in slots 5B, 5C, 6B, 6C, 7B and a slot not shown in cap 3B in a manner substantially the same as protuberance 8 was in its respective slots.

The relationship between relatively short slots 5C, 6C, 7C and the larger (longer) slots 5B, 6B, 7B is also substantially the same except that the relatively long slots 5B, 6B, and 7B may be all of the same to each other length since the settings of the implement in this type of pen structure do not depend so much upon longitudinal slide of the cap. Said slots merely have to be long enough to allow sleeve 3C to assume position over valves 1A and 2A.

Slot 6B is in line with solid walls of sleeve 3C, thus protuberance 8A when engaged in said slot, will prevent cap 3B from turning when the implement is used for writing at high altitudes with

valves 1A and 2A remaining safely compressed under solid walls of sleeve 3C.

Slot 5B, in line with off-sets 12 and 12A, when engaged in protuberance 8A, will keep cap 3B and sleeve 3C from turning when the implement is engaged for writing with valves 1A and 2A remaining open through said off-sets 12 and slot 7B, in line with offset 12B, when engaged with protuberance 8A, will keep cap 3B and sleeve 3C from turning when the implement is used for writing with ink duct valve 1A open through off-set 12B, and the air duct valve 2A locked under opposite solid section of sleeve 3C. Slots 5C, 6C and 7C are adequately short for any one of them engaged with protuberance 8A to stop cap 3B from sliding far enough towards cover 9A to release nib 10A or either of the valves 1A and 2A under solid length of sleeve 3C, and are adequately deep to prevent cap 3B from turning while the implement is carried around.

Cap 3B wall sections or notches separating slots 5B from 5C, 6B from 6C, 7B from 7C are lower than wall sections or notches of said cap separating said pairs from each other, thus it takes less effort to engage protuberance 8A from slot 5B into 5C, 6B into 6C, 7B into 7C than from either slot of each pair into either slot of another pair. As in reference to Figures 1 and 2, this difference of efforts may be again brought to bear a difference of one from two hands average effort, and, in this case also, can be bordered by means suitable to required manufacture: difference in lengths in the separating notches, friction of cap 3B extreme rear edge against a convexity on or over the barrel, a friction of cap 3 against the barrel or inner walls of cover 9A, an adequate spring between sleeve 3C and a convexity on or over the barrel, etc.

Any of these methods would serve the purpose and can be determined in the course of manufacture dependent upon desired cost and pen structure.

An operator of a pen shown in Figures 3 and 4 needs not to concern himself with the details of concealed mechanism to be in a position to operate the implement easily, efficiently and, while the pen is in the same setting, with one hand only, and without looking at the pen.

Also without looking and still with one hand only the operator may reset the implement into a locked position, unlock the pen and reset to writing position.

Slot 5B may be indicated on the outside of the cap, for instance, with one dot, slot 7B with two dots, slot 6B—three dots. The clip may be secured stationarily to the barrel always in line with nib 10A and protuberance 8A.

Hence the operator should concern himself with following rules only:

To fill the implement only when it is open with 1 dot in line with clip. After filling, if no change of altitude or temperature is anticipated, to close the implement with one hand only and turn the cap as far as one hand effort easily permits, then let the implement alone.

To open, to pull the cap up with fingers of one hand, turn the cap with the same fingers in direction it turns and as far as it goes with one hand easy effort, then push the cap with the same fingers towards clip held in the palm of the hand.

If after filling the implement is to be taken to higher altitude or temperature, to take the cap into one hand and the cover with clip into another hand, pull cap from cover as far

as it goes and, while in such pulled position, turn either way until two or three dots line up with clip. Then to let the pen go after locking it with one hand effort as described in reference to one dot setting.

Two dots lining is for slight change in altitude or temperature, three dots lining—for great change, such, for instance, as flight in stratosphere.

While specific embodiments of this invention are herein shown and described, it is and will be clearly understood, of course, that broad variations within the scope of accompanying claims may be resorted to without jeopardizing this patent protection, and that the various details of constructions may be varied through a wide range without departing from the principles of this invention as described in one or more of following claims, and it is therefore not the purpose to limit the patent granted hereon otherwise than necessitated by the prior art and the said scope of the appended claims.

What is claimed as the invention is:

1. In a stylus-like retractile marking implement with slidable and rotary cap and a shut-off mechanism automatically engaged when the instrument is closed, and engaged or disengaged, dependent upon different settings of said cap in relation to the barrel, when the instrument is open, a protrusion device with slot apparatus by which device the instrument may be adjusted and kept in a desired setting, and comprising a plurality of parallel slots lengthwise with the instrument and in a slidable and turnable housing, which slots are individually engageable against a protuberance in a cooperating housing, whereby the rotary and slidable parts are held in different and set positions dependent upon circumferential location and depth of the engaged slot.

2. In a stylus-like retractile marking implement with slidable and rotary cap and a shut-off mechanism automatically engaged when such writing instrument is closed, and engaged or disengaged, dependent upon different settings of said cap, when the instrument is open for writing, a protrusion device with slot apparatus by which device said cap may be kept in a desired adjusted setting, and comprising a housing slid- 45 able and rotary over another housing, a protuberance in a pen housing in slidable relationship with another housing, said protuberance engage-

able in one or another of a plurality of separate, longitudinal and parallel slots in said other housing lengthwise with the pen and open towards the protuberance when the housing is turned to a dependent position whereby the slot is opposite the protuberance.

3. In a stylus-like retractile marking implement with slidable and rotary cap and a shut-off mechanism automatically engaged when the pen is closed, and engaged or disengaged, dependent upon different settings of said cap, when the pen is open, a protrusion device with a slot apparatus by which device said pen may be adjusted and kept in a desired setting and locked and open in the same setting with a relatively lesser effort than is required to reset the pen into another setting by means of said device and apparatus, and comprising in a slidable pen housing a protuberance engageable successively in one or another of a plurality of separate, longitudinal and parallel slots in a pen housing which is opposite the protuberance in the other housing and dependent thereupon and is rotary when slid away from the protuberance, and is stationary therewith when the latter is engaged in one or another of said slots which are lengthwise with the pen and open towards the protuberance, and each has at its open end one of its longitudinal edges longer than the opposite edge, the latter forming an off-set step towards the housing-outer-edge nearest to the protuberance, whereby said step clears from the protuberance before its housing's said outer edge when an effort is made to slide the housing away from the protuberance and rotate it for a different setting in relation therewith.

JOSEPH F. KINGSLY.
